US00D546138S

(12) **United States Design Patent** (10) **Patent No.:** **US D546,138 S**
(45) **Date of Patent:** **** Jul. 10, 2007**

(54) **EXTRUDER FOR FOOD MIXTURES**

(75) Inventors: **Marcus Vagnby**, Copenhagen (DK);
Kwok Kuen So, 2/F, Chuan Yuan
Factory Building, 342-344 Kwun Tong
Road, Kwun Tong, Kowloon (HK)

(73) Assignee: **Kwok Kuen So**, Kowloon (HK)

(**) Term: **14 Years**

(21) Appl. No.: **29/248,784**

(22) Filed: **Sep. 1, 2006**

(51) **LOC (8) Cl.** **07-04**

(52) **U.S. Cl.** **D7/672; D7/669**

(58) **Field of Classification Search** **D7/672,**
D7/669, 665, 674; D8/14.1; 222/43, 44,
222/256, 257, 260, 287, 325-327, 333, 386,
222/390-392; 425/376.1, 87, 190-192 S,
425/280

See application file for complete search history.

(57) **CLAIM**

The ornamental design for extruder for food mixtures, as shown and described.

DESCRIPTION

FIG. 1 is a right side view of the article.

FIG. 2 is a left side view of the article.

FIG. 3 is a front view of the article.

FIG. 4 is a rear view of the article.

FIG. 5 is a top view of the article.

FIG. 6 is a bottom view of the article.

FIG. 7 is a right side view of the article with the piston in an innermost position; and,

FIG. 8 is a right side view of the article with the piston in an outermost position.
